UNITED STATES PATENT OFFICE.

ARCHIBALD F. REDDIE, OF PHILADELPHIA, PENNSYLVANIA, ASSIGNOR TO
McCALLUM & McCALLUM, OF SAME PLACE.

DESIGN FOR CARPET.

SPECIFICATION forming part of Design No. 23,991, dated February 5, 1895.

Application filed January 8, 1895. Serial No. 534,262. Term of patent 3½ years.

To all whom it may concern:

Be it known that I, ARCHIBALD F. REDDIE, residing at Philadelphia, in the county of Philadelphia and State of Pennsylvania, have 5 invented and produced a new and original Design for a Carpet or other Fabric, of which the following, taken in connection with the accompanying drawing, is a specification and description.

10 In the accompanying drawing A, is the body; B, the border, and A and B, a complete carpet, and said drawing conveys the effect upon the eye in such manner that a clear understanding of that which constitutes my invention and imparts a peculiar or distinctive 15 appearance to the carpet to which it is applied, is readily understood by an inspection thereof.

Obviously my design for a pattern may be 20 applied to a Wilton, Brussels, velvet or other

carpet in such colors as may be designed and will impart a peculiar or distinctive appearance thereto, so that the same will embody my invention and be readily distinguishable by reason of their effect upon the eye of an 25 observer.

What I claim as my invention, and desire to secure by Letters Patent, is—

1. In a design for a carpet, the body A, substantially as shown.

2. In a design for a carpet, the border B, substantially as shown.

3. The design for a carpet consisting of the body A, and border B, substantially as shown.

In testimony whereof I have hereunto 35 signed my name.

ARCHIBALD F. REDDIE.

In presence of—

HARRY O. SWEARER,

ANNA K. MAY.
